Application December 10, 1941, Serial No. 422,396

3 Claims. (Cl. 132—1)

My invention relates to a new and improved mount for bobby pins.

The principal object of my invention is to provide a cheap mount upon which bobby pins can be frictionally supported with their shanks spaced or separated from each other, and from which a bobby pin can be readily removed, while separating the tips of the shanks of the bobby pin, during the operation of removing the pin.

Other objects of the invention are set forth in the annexed description and drawing, which illustrates a preferred embodiment thereof.

Fig. 1 is a front elevation illustrating the improved holder or mount with the bobby pins mounted thereon. In this figure, the bobby pins are substantially in normal closed position, because their tips are only slightly separated.

Fig. 2 is a sectional view on the line 2—2 of Fig. 1. It illustrates how the bobby pin which is being removed from the mount is frictionally held on a bar or rail of the mount, with the shanks of said bobby pin in fully spaced relation.

Figs. 3 and 4 are respectively sections on the lines 3—3 and 4—4 of Fig. 1.

The bobby pin of commerce is made of resilient metal, and the tips of the shanks of said bobby pin are normally resiliently pressed against each other. The tips of the shanks of such pins must be separated from each other, in order to insert such pins in curlers, and for various other purposes. It is difficult to separate the tips of the shanks of the bobby pin, and numerous expensive and complicated devices have been proposed for this purpose.

According to the invention, I provide a simple card mount 1 which is shaped so that the tips of the shanks of each bobby pin B can be suitably separated, as part of the operation of removing the respective bobby pin from the mount. For convenience, the device is described with reference to its vertical position, but said device can be held in any position.

The drawing shows a mount 1 which is provided with a bar 2, so as to provide openings W. At its lower end, the mount 1 is provided with a flap or supplemental member 3. The ends of the supplemental member 3 are connected to the mount 1, by means of wire stitches 4 or in any other suitable manner.

The front and rear faces of the mount 1 are planar and parallel to each other and identical. The mount 1 can be made of cardboard or other suitable rigid material, which is preferably somewhat flexible and resilient.

The bobby pins are mounted so that the bot-

tom end-portions of the shanks of the bobby pin are separated from each other below the openings W, by the respective intermediate portion of the mount 1. The bottom end-portions of the front shanks of the bobby pins are located between the respective portions of the mount 1 and the supplemental member 3. The resilient shanks of the bobby pins frictionally engage the mount 1.

In order to remove a bobby pin B from the mount 1, said bobby pin is slid upwardly until the tips of the shanks of said bobby pin are located between the top and bottom edge walls of the respective opening W.

The bobby pin B is then turned until its axis is substantially horizontal, so that the tips of the shanks of the bobby pin are widely separated from each other by the respective intermediate bar 6 of the mount 1. The bobby pin can be frictionally retained in this horizontal position which is shown in Fig. 2, on the rail or bar 6. Likewise, upon removing the bobby pin by sliding the same horizontally off the bar 6, the separated shanks of the bobby pin can be easily held separated from each other by the thumb and forefinger of the user, so that the tips of the shanks of the bobby pin are widely spaced from each other, when the bobby pin B is finally wholly removed from the mount 1. It is then unnecessary further to separate the tips of the shanks of the bobby pin for insertion into a curler or into the hair.

The improved mount is extremely simple and it can be made at low cost, and the bobby pins can be very easily assembled with said mount.

In practicing the improved method, the bobby pin is placed on a mount on which the bobby pin is frictionally retained, with the tips of the shanks of the bobby pin preferably slightly separated from each other. The shanks of the bobby pin are then substantially parallel to each other. The bobby pin is then tilted relative to a portion of this mount, in order to increase the spacing between the tips of said shanks, and the bobby pin is then removed from the mount while the separated tips of the shanks are held separated from each other.

The width of the bar 6 exceeds the thickness thereof. Hence, the spacing between the tips of the shanks depends upon the inclination of the bobby pin relative to said bar 3. Further details are shown in the drawing, which is substantially to scale.

As shown in Fig. 2, the tips of the shanks

frictionally grip an imperforate part of the mount 1.

When the bobby pin is in the position shown in Fig. 2, one of the shanks of the bobby pin which is being removed, extends through the respective opening W. The bobby pin is slidable and tilttable relative to the mount when the bobby pin is in the original position of Fig. 1, in order to extend said shank through said opening W, as soon as the bobby pin has been moved relative to the mount, from the position shown in Fig. 1 to the position shown in Fig. 2. When said shank extends through said opening W, the shanks abut the edges of bar 6. Said bar 6 is dimensioned, then to separate the tips of said shanks so that the tips of said shanks are separated sufficiently to enable the bobby pin to be used, without additionally separating said tips. The invention is not limited to a device in which the tips of the shanks abut an imperforate part of the mount, when the bobby pins are originally assembled on the mount in the position shown in Fig. 1, in which the top edge-wall of the mount abuts the inner wall of the bobby pin at the bight of the bobby pin.

Each opening W has a substantially straight edge wall 1 which is adjacent and which is substantially parallel to a corresponding and substantially straight edgewall of the mount 1.

The edge of the mount 1 which abuts or which is close to the loop-end of the bobby pin may be designated as the first edge of said mount 1. Said mount 1 has a second edge which is opposed to said first edge, namely, the bottom edge of the mount 1 in Fig. 2. The opening W is located between said first edge and said second edge.

I have described a preferred embodiment of my invention, but it is clear that numerous changes and omissions can be made without departing from its spirit.

I claim:

1. A mount which has a front face and a rear face, said faces being substantially planar and parallel to each other, said mount having a first edge and also having a second edge which is opposed to said first edge, said mount having an opening therein between said first edge and said second edge, a bobby pin mounted upon said mount, said mount being located between the shanks of said bobby pin, said shanks extending across said opening, said shanks abutting and frictionally gripping said faces at an imperforate part of said mount, said imperforate part being located between an edge of said opening and said second edge, said first edge substantially abutting the inner surface of the loop of said bobby pin, said bobby pin being slidable in the direction of its longitudinal axis relative to said mount until the tips of said shanks are located in said opening, said bobby pin being then tilttable relative to 60

said mount to a position in which one shank of said bobby pin abuts said first edge and the other shank of said bobby pin then abuts the edge of said opening which is next adjacent to said first edge and said other shank extends through said opening, the distance between said first edge and the respective next-adjacent edge of said opening being greater than the distance between said shanks when said bobby pin is in normal closed position, said tilted bobby pin being then slidable off said mount in a direction parallel to the longitudinal axis of said bobby pin in said tilted position.

2. A mount which has a first edge and a second edge which is opposed to said first edge, said mount having an opening therein, which is located between said first edge and said second edge, a bobby pin mounted on said mount, said mount being located between the shanks of said bobby pin, said shanks extending across said opening, said shanks frictionally and releasably gripping said mount between said second edge and the next-adjacent edge of said opening, said bobby pin being slidable in the direction of its longitudinal axis relative to said mount to a position in which the tips of said shanks are located in said opening, said bobby pin being then tilttable relative to said mount to a position in which one of said shanks abuts said first edge and the other shank extends through said opening in abutment with the edge of said opening which is next-adjacent said first edge, the distance between said first edge and the respective next-adjacent edge of said opening being greater than the distance between said shanks when said bobby pin is in normal closed position, said tilted bobby pin being then slidable off said mount in a direction parallel to the longitudinal axis of said bobby pin in said tilted position.

3. A device for releasably frictionally holding a bobby pin and for separating the tips of the shanks of said bobby pin, said device having a separating-member and an opening which is directly adjacent said separating-member, said device also having a holding-member which is shaped to enter between said shanks and to be releasably frictionally engaged by said shanks, said opening being located between said separating-member and said holding-member, said device being dimensioned to be located between said shanks with shanks extending across said opening and with said holding-member thus located between and releasably holding said shanks, the width of said separating-member exceeding the thickness of said holding-member, said opening being greater than the thickness of either shank.

ABNER JOSEPHS.
